UNITED STATES PATENT OFFICE.

FREDERICK W. GOUDY, OF FOREST HILLS GARDENS, NEW YORK, ASSIGNOR TO AMERICAN TYPE FOUNDERS COMPANY, OF JERSEY CITY, NEW JERSEY, A CORPORATION OF NEW JERSEY.

DESIGN FOR A FONT OF TYPE.

55,267.

Specification for Design.

Patented May 25, 1920.

Application filed December 2, 1919. Serial No. 342,040. Term of patent 14 years.

To all whom it may concern:

Be it known that I, FREDERICK W. GOUDY, a citizen of the United States, residing at Forest Hills Gardens, Long Island, in the county of Queens and State of New York, have invented a certain new, original, and ornamental Design for a Font of Type, of which the following is a specification.

The accompanying drawing shows the face of each letter and character composing said font of type and clearly illustrates the new, original and ornamental character thereof.

What I claim as new, is:

The ornamental design for a font of type shown in the accompanying drawing.

In witness whereof I have hereunto set my hand and seal at Forest Hills Gardens, Long Island, N. Y., this 28th day of November, A. D. nineteen hundred and nineteen.

FREDERICK W. GOUDY. [L. S.]
